US00D548352S

(12) **United States Design Patent** (10) Patent No.: **US D548,352 S**
Maesawa et al. (45) Date of Patent: ** Aug. 7, 2007

(54) **ELECTRIC MASSAGER**

(75) Inventors: **Naoki Maesawa**, Tokyo (JP); **Taro Mochida**, Tokyo (JP)

(73) Assignee: **Matsushita Electric Works, Ltd.**,
Osaka (JP)

(**) Term: **14 Years**

(21) Appl. No.: **29/244,670**

(22) Filed: **Dec. 13, 2005**

(30) **Foreign Application Priority Data**

Jun. 15, 2005 (JP) 2005-017288

(51) **LOC (8) Cl.** **28-03**

(52) **U.S. Cl.** **D24/212**

(58) **Field of Classification Search** D24/200,
D24/212, 213, 215; 601/23, 27, 28, 29, 30,
601/34, 35, 36, 46, 61, 90, 95, 97, 84-86

(57) **CLAIM**

The ornamental design for an electronic massager, as shown and described.

DESCRIPTION

FIG. 1 is a perspective view of the design according to the invention.

FIG. 2 is a top view of the design according to the invention.

FIG. 3 is a bottom view of the design according to the invention.

FIG. 4 is a front view of the design according to the invention.

FIG. 5 is a rear view of the design according to the invention.

FIG. 6 is a left side view of the design according to the invention.

FIG. 7 is a right side view of the design according to the invention.

FIG. 8 is a perspective view of the design in an alternative position of the design according to the invention; and,

FIG. 9 is a perspective view of the design in an alternative position of the design according to the invention.

The portions in even broken lines are for illustrative purposes only and form no part of the claimed design.
